ATT'Y.

UNITED STATES PATENT OFFICE.

FRANK ABORN, OF CLEVELAND, OHIO.

COMPASS-JOINT.

SPECIFICATION forming part of Letters Patent No. 499,193, dated June 13, 1893.

Application filed December 22, 1892. Serial No. 455,983. (No model.)

To all whom it may concern:

Be it known that I, FRANK ABORN, residing in Cleveland, county of Cuyahoga, State of Ohio, have invented an Improvement in Hinge-Joints, of which the following description, in connection with the accompanying drawings, is a specification, like letters on the drawings representing like parts.

This invention relates to a novel construction of hinge joint especially applicable, among other things, to dividers, and like instruments.

In accordance with my invention, the hinge joint is composed of two members or parts, one of which, is provided with conically-shaped spring portions, hereinafter designated as spring ears, and which are adapted to be inserted between correspondingly shaped parts or ears on the other member, and frictionally held to the ears of the second part or member. The conical ears may extend inward or outward as desired, and when the members of the hinge joint are fitted together, they may be easily adjusted toward each other with great smoothness of action, and when so adjusted, the said members are maintained in their adjusted position until positively moved. The members of the hinge joint may be extended to form the legs of dividers and like instruments, employed in drawing, and the instruments thus made are simple, strong, durable, light, cheap, and are uniformly adjustable toward and from each other with great smoothness of action.

My invention in a hinge joint, therefore, consists in the combination with one member provided with laterally extended ears, of a second member having laterally extended spring ears fitted into or between the laterally extended ears of the first member and frictionally engaging the said ears of the first member, substantially as will be described.

Other features of my invention will be pointed out in the claims at the end of this specification.

Figure 1, is a side elevation of an instrument embodying my invention; Fig. 2, a longitudinal section of the instrument shown in Fig. 1, on the line 2—2; Fig. 3, a transverse section of the instrument on the line 3—3; Fig. 4, a transverse section on the line 4, Fig.

1; Fig. 5, a transverse section on the line 5, Fig. 1.

Referring to Fig. 1, a , a' represent the legs of a pair of dividers, which in the present embodiment of my invention constitute the two parts or members of the improved hinge joint. The parts or members a , a' are provided at one end with laterally extended ears a^2 a^3 , a^4 a^5 , respectively, which are preferably made integral with the said parts or members, and for the best results, the said ears and parts or members are made of sheet metal, preferably steel. The ears of one member, herein shown as the ears a^2 a^3 of the member a are inserted between the ears a^4 a^5 of the other member, and the ears a^2 a^3 are made so as to possess spring action and form spring ears, which frictionally engage the ears a^4 a^5 and thus unite the members a , a' together. The ears of the members a , a' are made conical in shape, as shown in the drawings, and they may be extended inward or outward as desired. The member a , is extended to form one leg of the dividers and is provided at its lower end with a tubular portion b , herein shown as slotted longitudinally to form spring jaws to receive and firmly hold a pencil or other marking device b' , and the member a' is extended to a substantially sharp point to form the needle or prick point of the dividers.

As represented in Fig. 4, the portion of the member a , above the holder b , is made substantially semi-circular to effect a saving in stock, when the parts comprising the member a are made in one piece as herein represented. The ears a^4 a^5 of the member a' , may and preferably will be made to possess spring action but they may be made rigid. If desired, the ears on the members a , a' may have extended through them a pin or swivel b^2 , shown only in Fig. 3 by dotted lines, but in practice, I prefer to omit the swivel or pin as the conical shape of the spring ears serves to frictionally hold the members a , a' securely together, and prevents the said members becoming disconnected by a force such as would be ordinarily exerted in opening the dividers in practice.

The members a , a' are preferably made from sheet metal and each in one piece, and when shaped to form a drafting instrument,

such as a pair of dividers as herein shown, the said instrument possesses the attributes of simplicity, durability, uniformity and self-adjustment of action, lightness, strength and cheapness.

5 The frictional hinge joint uniting the two members together, enables the said members to be adjusted toward and from each other with facility and smoothness of action, and 10 maintains the said members in their adjusted position until positively moved.

15 I have herein shown and described the frictional hinge joint as embodied in a drafting instrument, but I do not desire to limit my invention in this respect as the said joint is 20 applicable to other uses to which the hinge joint may be adapted by changing the shape of the members a , a' .

I claim—

25 1. In a hinge joint, the combination with one member provided with conically shaped ears, of a second member having conically shaped spring ears fitted into or between the conically shaped ears of the first member and 30 frictionally engaging said ears of the first member, substantially as described.

35 2. In a drafting instrument, the combination with a member or leg a' provided at one end with a point, and having at its opposite end two conically shaped ears, of the leg or member a provided at one end with a holder for a marking device and having at its other end conically shaped ears co-operating with

the ears on the member a' and frictionally securing the member or leg a to the member 35 or leg a' , substantially as described.

3. In a drafting instrument, the combination with a member or leg a' composed of sheet metal, shaped to form a point at one end and two laterally extended ears at the opposite end, of a member a composed of sheet metal shaped to form at one end a holder for a marking device and at its other end two laterally extended ears co-operating with the ears on the member a' to frictionally secure 45 the said members together, substantially as described.

4. In a drafting instrument, the combination with a member or leg a' composed of sheet metal, shaped to form a point at one 50 end and two ears at its opposite end, of a member a composed of sheet metal shaped to form at one end a tubular holder b , above which the member a is reduced in circumference, and at its opposite end spring ears co-operating with the ears on the member a' to frictionally secure the said members together, 55 substantially as described.

In testimony whereof I have signed my name to this specification in the presence of 60 two subscribing witnesses.

FRANK ABORN.
